CLAIM

The ornamental design for a cat tunnel, as shown and described.

DESCRIPTION

FIG. 1 is a front, top and side perspective of a cat tunnel design showing my new design.

FIG. 2 is a side view of a cat tunnel design showing my new design.

FIG. 3 is a front view of the side of a cat tunnel design showing my new design.

FIG. 4 is a rear view of the side of a cat tunnel design showing my new design; and,

FIG. 5 is a top view of the cat tunnel, the bottom view being identical thereof.

The broken lines in the drawings illustrate portions of the cat tunnel that form no part of the claimed design.
